CLAIM

The ornamental design for a projectile, as shown and described.

DESCRIPTION

FIG. 1 is a perspective view of a projectile showing my new design;

FIG. 2 is a left elevation view thereof;

FIG. 3 is a front elevation view thereof, which is the same as the rear elevation view, top plan view, and bottom plan view because the projectile is symmetrical around its longitudinal axis;

FIG. 4 is a right elevation view thereof;

FIG. 5 is a perspective view of another embodiment of a projectile showing my new design;

FIG. 6 is a left elevation view of the projectile of FIG. 5; FIG. 7 is a front elevation view of the projectile of FIG. 5, which is the same as the rear elevation view, top plan view, and bottom plan view because the projectile is symmetrical around its longitudinal axis;

FIG. 8 is a right elevation view of the projectile of FIG. 5; FIG. 9 is a perspective view of another embodiment of a projectile showing my new design;

FIG. 10 is a left elevation view of the projectile of FIG. 9; FIG. 11 is a front elevation view of the projectile of FIG. 9, which is the same as the rear elevation view, top plan view, and bottom plan view because the projectile is symmetrical around its longitudinal axis; and,

FIG. 12 is a right elevation view of the projectile of FIG. 9. The dot-dash lines are provided to show the boundary of the claim and form no part of the claim. The dash-dash lines showing portions of a projectile are provided for the purpose of illustrating environment and form no part of the claimed design.
